* cited by examiner

Primary Examiner—Cathron Brooks*Assistant Examiner*—Austin Murphy*(74) Attorney, Agent, or Firm*—Wolf Greenfield & Sacks(57) CLAIM

The ornamental design for a stapler, as shown and described.

DESCRIPTION

FIG. 1 is a side, top, rear perspective view of the stapler; FIG. 2 is a left side view thereof, the right side view thereof being a mirror image thereof;

FIG. 3 is a front view thereof;

FIG. 4 is a rear view thereof;

FIG. 5 is a top view thereof; and,

FIG. 6 is a bottom view thereof.

The broken lines in the figure drawings are included for the purpose of illustrating environment and form no part of the claimed design.
